(57) **CLAIM**

We claim the ornamental design for a refrigerator induction controller, as shown and described.

DESCRIPTION

FIG. 1 is a front view of a refrigerator induction controller showing our new design;

FIG. 2 is a rear view thereof;

FIG. 3 is a left side view thereof;

FIG. 4 is a right side view thereof;

FIG. 5 is a top view thereof;

FIG. 6 is a bottom view thereof; and,

FIG. 7 is a space diagram thereof.

1 Claim, 7 Drawing Sheets

FIG. 1

FIG. 2

FIG. 3

FIG. 4

FIG. 5

FIG. 6

FIG. 7
